UNITED STATES PATENT OFFICE.

HOWARD L. QUICK, OF NEW YORK, N. Y.

APPARATUS FOR DYEING FABRICS.

1,195,606.

Specification of Letters Patent. Patented Aug. 22, 1916.

Original application filed January 7, 1914, Serial No. 810,757. Divided and this application filed July 30, 1914. Serial No. 854,026.

To all whom it may concern:

Be it known that I, HOWARD L. QUICK, a citizen of the United States, and a resident of the borough of Brooklyn, city of New York, county of Kings, and State of New York, have invented certain new and useful Apparatus for Dyeing Fabrics, of which the following is a specification.

This application is a division of my Patent Number 1,131,270 of March 9, 1915, filed on the 7th day of January, 1914, Serial Number 810,757.

My invention relates to an apparatus for treating fabrics.

15 My invention is especially advantageous in the processes of mercerizing, stripping or boiling off, bleaching, dyeing, finishing, weighting silks, and treating woolen goods. It is, in fact, advantageous wherever a large 20 quantity of fabric is to be treated at a time by the action of a liquor; especially where several successive treatments are required; and wherever the action of the liquor must be substantially uniform upon all parts of 25 the fabric.

The objects of my invention are, to save time and expense and to produce uniform results.

Heretofore it has been customary in treating fabrics, especially in dyeing, bleaching and similar processes, to mount a large roll of fabric upon the beam of a jigger, reel the fabric upon another beam, passing the fabric through a suitable liquor; and to jig the 35 fabric back and forth by winding it from one beam upon the other, all the time passing the fabric through the liquor. Each step in the process required that the whole piece of fabric (generally about 5000 yards) 40 be jigged back and forth from one beam to the other. If, for instance in dyeing, it was necessary to subject the fabric to liquors of two or more different colors it was necessary to jig the fabric through each liquor 45 several times; and very often it was necessary to jig it through water to wash it, between the different dyeing operations. Each time the fabric is jigged from one beam to another considerable time, labor and power 50 are required. For a 5000 yard piece the average time consumed in jigging from one beam to another was about 25 minutes; and each step in the process required one or more

such operations. Furthermore, it was necessary to remove the fabric from the jig and 55 to dry it upon a separate machine. In addition to the time and labor required for these several operations the fabric was subjected to more or less stress which was unequal. Furthermore, different portions of 60 the whole piece were sometimes unequally affected by the liquor.

The object of my invention is to avoid many if not all, of these objections. With my present invention it is possible to treat 65 the fabric successively with different liquors without necessarily handling the fabric between treatments.

The broad principle of my invention resides in providing a machine wherein the 70 fabric wound in a roll upon a suitable support has the liquor introduced therein and forced therethrough by centrifugal force as the roll is rapidly revolved.

In the drawings forming part of this application, Figure 1 is a plan view of the machine. Fig. 2 is a cross section thereof, taken on the line 2—2 of Fig. 1, and showing the cover down or closed and, Fig. 3 is a longitudinal sectional view through the 80 roller and associated parts.

I have shown a very simple and convenient arrangement for carrying out my objects. This consists of a casing 1 for enclosing the roll of fabric to prevent the 85 scattering and loss of liquor; and it comprises a stationary casing 1 mounted upon suitable standards 2, 3; and of a cover 4 hinged at 5. Outside the casing there is a shaft 6 having fast and loose pulleys 7, 8, to 90 which power may be applied by means of a belt 9, operated from any suitable source. This shaft is adjustable, lengthwise, in its bearings 10 by means of a screw 11 operated by the wheel 12. Fixed to the shaft there is 95 a friction disk 13 which is arranged to act upon a corresponding cone 14 to revolve the shaft 15. The shaft 15 projects through the standard 3 and on one end it is provided with a chuck 16, arranged inside the casing. In the standard 2 there is journaled a bearing block 17 which carries a sleeve 18, alining with the shaft 15; and on one end thereof is a chuck 19, also arranged inside the casing. The journal block 17 is adjustable in the journal 20 by means of a screw 100

21 operated by the wheel 22. With this arrangement the chuck member 19 may be adjusted toward and from the chuck member 16 to adapt the device for shells of different 5 lengths.

The shell shown herein consists of a tubular member 23 having a bore 24, closed at one end 25 and open at the opposite end 26. One end of the shell has a trunnion 27 for 10 entry into the chuck member 16; and the opposite end has a trunnion 28 for entry into the chuck member 19. The latter trunnion has a bore 29 for a purpose which will appear.

15 Throughout the greater portion of its length the shell is perforate or of honeycomb structure. I have shown the wall as provided with regularly spaced openings 30 of uniform area, separated by the walls 31. 20 These openings extend from the bore 24 to the exterior of the shell.

In order to insure the passage of the liquor evenly through all parts of the roll of fabric and to prevent it, for any reason, from passing 25 out of the roll in a direction endwise thereof, I have provided suitable end flanges for closing the ends of the fabric roll. I have shown two such flanges 32 directed at right angles to the shell. These are carried 30 upon hubs 33 which are adjustable along the shell and are adapted to be secured thereto, in different positions, by the set screws 34. These hubs, 33, extend over portions of the shell so that when moved inwardly from 35 their extreme outer positions, as shown in Fig. 3, they will effectively close some of the openings 30. That is, they close the openings not lying within any particular roll of fabric which is of less length than the 40 maximum for which the machine is designed. The flanges 32 are so made as to prevent the escape of the liquor between the ends of the roll and the flanges, and to thus insure the passage thereof laterally through 45 the roll. For this purpose the flanges are provided with concentric corrugations 32'.

To prepare the fabric for treatment it is first wound tightly and evenly upon the shell 23. This may be done in the machine 50 herein shown or it may be done upon any machine adapted to the purpose. In order to obtain proper results the fabric should be wound upon the shell in smooth, even layers. It should also be wound tightly; 55 and, in some processes, such as mercerizing, the fabric should be wound under considerable tension. It may be here stated that one important advantage of my invention as applied to mercerizing is, that the fabric 60 may be wound under an even tension and, therefore, all parts of the fabric may be subjected to treatment while under equal stress or tension. When the fabric has been properly wound upon the shell the hubs (and 65 their flanges) are moved along the shell to

bring the corrugated surfaces 32' against the ends of the roll of fabric; and they are there secured by tightening the screws 34.

If the fabric has been wound in the machine herein shown it is ready to be treated; 70 but if wound in a separate machine the shell and fabric must be placed in position. This may be done by placing the trunnion 27 into the chuck 16; and by bringing the trunnion 28 into line with the chuck 19. The hand 75 wheel 22 is then operated to move the journal 17, sleeve 18 and chuck 19 until the latter engages the trunnion 28. A pipe 36 having one end 37 closed and having ports 38 arranged at equal distances therealong, is 80 inserted through the sleeve 18 and trunnion 28 until it extends the full length of the fabric roll. This pipe need not revolve but may be stationarily held in a standard 39. The pipe 36 is connected with the source of 85 supply of treating liquor, such for instance, as a tank 40 arranged above the receptacle.

The parts having been arranged as above set forth, the belt 9 is shipped to the fast 90 pulley 8 to start the operation of the shaft 6. The hand wheel 12 is now operated to shift the shaft 6 and bring the friction drive disk 13 into contact with the cone 14. When this has been done the shell 23 and 95 its roll of fabric will be revolved. These should be revolved very rapidly, say at the rate of several hundred revolutions a minute. The cover 4 having been lowered, the treating liquor is allowed to flow through the pipe 36. It will discharge 100 through the ports 38 of the pipe 36 and will pass through the apertures of the shell 23, entering the roll of fabric at the interior thereof.

The centrifugal force caused by the rapid 105 revolution of the roll will cause the liquor to pass through the fabric and discharge into the casing 1. The liquor will run to the bottom of the casing and it may be drawn off through the pipe 41 and raised, as by a 110 pump, to the tank 40, to be used over again. The centrifugal action will cause the liquor to very rapidly pass through all portions of the fabric roll; and, if the fabric has been 115 evenly wound, the liquor will act more uniformly thereon than in any method of treatment known to me.

If a dyeing liquor is admitted through the pipe 36 it will be forced through all portions of the fabric and will evenly dye it. If two or more liquors are required to produce the desired color they are each, in their turn, fed through the pipe 36, so that they affect the fabric in the desired manner. In the process of mercerizing, a caustic soda solution is 125 fed through the pipe 36 and is driven, by the centrifugal action, through the fabric. The latter, if wound under proper tension, will be mercerized by the action. If, as is 130 the case in many of the methods herein enu-

merated, it is necessary to wash the fabric between the separate treatments, this may be done without removing it from the machine. All that is required is to supply water through the pipe 36 when it will be forced through the fabric by the centrifugal action, the same as with the liquors. If, for any reason, the liquor should tend to pass out of the ends of the fabric roll it will enter the concentric grooves of the corrugated faces 32' of the flanges and it will form a seal to the oncoming liquid. In this manner the liquor is compelled to pass laterally through the roll of fabric.

The wall of the shell should be rather thick, as shown, in order that the apertures 30 will be of sufficient length to produce the desired result. If these apertures are long they retain sufficient of the liquor at all times to supply it to the fabric as fast as it is forced therethrough. Were these apertures insufficient there would be times when portions of the inner wall of the fabric roll would be temporarily without liquor and this would tend to make the process more or less irregular. These apertures not only tend to hold the necessary liquor always in readiness to feed into the fabric, but their defining walls prevent the liquor from splashing freely around in the shell.

By employing the machine herein described it is possible to treat the fabric evenly and with the least injurious effect upon it. It is also possible to carry out the

treatment in a much shorter time than heretofore, because the centrifugal action forces the liquor more rapidly through all parts of the fabric than where the latter is simply jigged through a bath.

Having described my invention, what I claim is:

1. A machine for treating fabrics, comprising a shell for holding a roll of fabric thereon and consisting of a tubular body having a bore, and having perforations therethrough, means for admitting liquor into the bore, flanges for closing the ends of the fabric roll, said flanges having grooved surfaces for abutting against the fabric roll, for the purpose set forth, and means for revolving the shell.

2. A machine for treating fabrics, comprising a shell for holding a roll of fabric thereon and consisting of a tubular body having a bore and having perforations therethrough, means for admitting liquid to the bore, flanges for closing the ends of the fabric roll, said flanges having surfaces formed with concentric grooves, said grooved surfaces abutting against the fabric roll, and means for revolving the shell.

Signed at the city, and State of New York, this 19th day of June, 1914.

HOWARD L. QUICK.
